UNITED STATES PATENT OFFICE.

JOHN GOOD, OF BROOKLYN, NEW YORK, ASSIGNOR TO GOOD INVENTIONS CO., OF NEW YORK, N. Y., A CORPORATION OF NEW YORK.

STARTING COMBUSTION ENGINES.

Application filed May 8, 1918. Serial No. 233,537.

The invention is an improved means for starting internal combustion engines of the kind in which the fuel is injected into the combustion space without previous mixture with the air charge with which it is to burn. Such engines ordinarily and most efficiently operate under compression pressures much higher than employed in mixture-supplied engines and are correspondingly more difficult to start by cranking. If used for automobile propulsion the capacity of the electric starting battery usually used in automobiles is quite inadequate for the purpose and hand cranking is exceedingly laborious and impracticable on that account. This invention comprises several features to facilitate the starting of such engines as well as high compression engines generally and thereby adapts them to convenient automotive use without undue increase in the electric load. One of said features consists in spinning the engine by the electric motor, with the engine compression relieved, in order to store kinetic energy in the spinning fly-wheel and other parts which is immediately thereafter utilized to turn the engine over a number of times when the compression has been restored and the fuel injection apparatus again rendered operative. Another of said features consists in automatically heating the engine at starting as by heating the air drawn into it, which may be done by or during the spinning and another consists in priming the engine by introducing a priming charge of liquid fuel into the heated intake air rendering it explosive so that the first power impulses in the engine may occur from combustion of such mixture independently of and preliminary to the normal fuel injection. Still other features of the invention will be made apparent to those skilled in this art in connection with the accompanying drawing, wherein—

Fig. 1 is a side elevation of an engine such as above described with the invention applied thereto, parts of the air heater being in section;

Fig. 2 is a vertical cross-section through one of the cylinder heads thereof showing the valve gear arrangement.

The said engine taken for illustration is represented as a four-cylinder, four-cycle engine with a substantial fly-wheel 1 peripherally geared to be driven by the pinion 2 of a starting motor 3. This may be the same type of motor and starting gear arrangement that is common in automobiles and motor boats but it will be observed that pinion 2 is relatively large in proportion to the fly-wheel and thereby adapted to rotate it at a correspondingly high velocity. Engagement of the pinion with the fly-wheel gear may be by any approved means, electrical or otherwise, as will be understood. The intake valve 4 and exhaust valve 5 of each cylinder are operated by valve levers 4^a and 5^a and cams 4^b and 5^b respectively on an overhead cam shaft 6 common to all of the cylinders and chain-driven from the crank-shaft 7, and the fuel injection is by means of a plunger 8 (Fig. 2) which is raised against the pressure of a spring 9 by a trip cam 10 and allowed to snap back by the spring pressure. The cylindrical chamber 75 in which the plunger works receives liquid fuel in measured amount through the duct 11 controlled by valve 12. Air from the engine cylinder is also admitted to the plunger chamber by a duct 13 uncovered by said so plunger near its outer or upper limit. The snap descent of the plunger desirably occurs when the air in the cylinder is under compression, being subject to variation and regulation in this respect, and descending 85 traps such air as may have entered from the cylinder, further compresses it, and forces it with the liquid fuel through a spiral-passaged spray nozzle 14 from which it issues into the combustion space of the engine as 90 a finely atomized spray. Such air as is thus admitted with the fuel is manifestly injected under a pressure considerably higher than that of the compression in the cylinder at the moment. The degree depends upon 95 the strength of spring 9. The trip cams, of which there is one for each injector plunger, are all carried on an auxiliary or injection cam shaft 15 driven by spiral gears 16 and 17 from the main camshaft 6. The spiral 100 gear 16 is splined to shaft 15 and adapted to be shifted longitudinally thereon by the lever 18 which will change the angular relation of the injection shaft to the cam shaft according to the pitch of the spiral teeth 105 on the gear. This serves as the means whereby the injection of fuel may be advanced or retarded by the operator.

The fuel valve 12 is spring-seated and opened by a lever 19 engaged by one of 110

the cams on cam-shaft 6 at an appropriate time and preferably during a non-pressure stroke of the engine piston. The details of this mechanism will constitute the subject 5 of another application; it will be sufficient here to explain that the cams and cam-lever arrangement for the several valves may be according to any design that will function in the manner herein stated. The 10 fuel admitted by the valve 12 may be measured in various ways prior to, or by the act of, its admission to the plunger chamber and one way of measuring it consists in allowing it to flow into the chamber under 15 the suction effect of the engine piston. By controlling the timing of the intake valve 4 or by throttling the air intake entrance 20, varying suction effects may be produced in the cylinder which are transmitted 20 through the nozzle and duct 13 to the plunger chamber to cause liquid fuel to be drawn in in correspondingly varying amounts which may be manifestly suited to the speed and load condition of the engine. The fuel 25 liquid is led to the fuel duct 11 by a pipe 21 shown broken off in Fig. 1. This pipe may be connected to a fuel receptacle under a suitable gravity head or under pressure in order to give adequately prompt flow of 30 viscous fluids.

By appropriate valve settings the engine structure above described may be used on the Diesel principle or it may have a fuel injection so advanced as to be completed before compression dead centre or even before half compression or during suction or it 35 may be spark-ignited if desired although it is intended and preferred that ignition shall take place by the heat of compression. It 40 will suffice for the present disclosure to assume that the working process involves a compression of fresh air to about 130 or 165 pounds per square inch with the fuel injection beginning at about 10 or more degrees before compression dead-centre although 45 subject to variation as above described. This working process will suffice to cause ignition by compression without the aid of hot walls or spark-plugs but the ignition 50 may be assured by a supply of heat from an auxiliary external source as presently explained.

The air supply to the intake manifold 22 is by way of one or both of two branched 55 air pipes 23 and 24, of which one, 24, is merely a connection between the manifold and the air entrance 20 while the other, 23, is formed in a coil or coil-shape and subject to contact with the hot exhaust gas 60 from the engine exhaust pipe 25. It therefore constitutes an air heater. The linked throttles 26 in each branch serve as a control of the proportion of air-flow through 65 each branch and thereby regulates the temperature of the air entering the engine. A

small turn-buckle 27 joining the crank-arms of the throttle 26, serves to adjust the one to the other according to the temperature and flow conditions desired. According to circumstances more or less heat may be supplied to the intake air in this manner, the least or none at all during full load and the most during idling. The coiled branch 23 is shown as constituting a section of the exhaust passage of the engine, the interior 70 of the coil being interposed between the exhaust pipe 25 and its exhaust outlet 28. The exterior of the coiled passage 23 is enclosed in a box 29 constituting the combustion space of an enclosed liquid fuel 75 burner 30 of which the exhaust outlet is shown at 31. By means of this heating apparatus the air in the branch 23 may be heated independently of or additionally to the heating by the engine exhaust. The 80 burner 30 may be the same as shown in my co-pending application No. 195,506, filed Oct. 9, 1917, being operated by a fan 32 driven by a small electric motor 33 and provided with a spark plug 34 so that on 85 closure of the motor circuit 35 automatic ignition and steady combustion is established and maintained in the box 29. The burner may use liquid fuel from the same 90 source as the motor fuel.

In the diagram of wiring, the motor circuit 35 is branched as a primary circuit to the rectangular figure which represents the usual spark coil and the wiring on the right of the coil is the secondary circuit leading 95 to the spark plug 34.

For starting such an engine as above described, the cam shaft 6 is mounted so that it can be shifted longitudinally and all the cams thereon are shaped or bevelled to accommodate such movement and they are so fashioned as to eliminate the normal engine compression and permit the fuel valve 12 to remain seated when the shaft has been shifted. This may be done either by causing said cams to hold the exhaust or intake valve constantly open or to double the timing of the valves so that the engine will work as a pump, drawing air in through the intake 20 and expelling it through the exhaust on each stroke. This is preferred and the engine builder will readily shape the cams to produce this alteration of the valve action without detailed instructions. The cam shaft 6 is held in normal position by a spring 36 and shifted endwise by suitable connections to a pedal or lever 37 as indicated. The lever 37 is shown as engaged with and operates a spring-pressed plunger 38 of a circuit closer, the contacts whereof are arranged in such manner that the liquid fuel burner 30 and the starting motor 3 are both energized by the storage battery 39 when the lever is operated to depress the plunger and shift the cam shaft. This re- 100 105 110 115 120 125 130 135 140

lieves the compression of the engine and coincidently spins the fly-wheel while the air inflowing to the engine is being heated by the burner. By reason of the lost motion 5 between lever 37 and plunger 38 it will be seen that the burner circuit 35 may be kept closed to continue the heating action after the cam shaft has been restored to normal working position, which is sometimes desirable, and the same arrangement permits the 10 burner to be started when the engine is running normally. That is to say by depressing the plunger far enough to close the burner circuit without closing the starting 15 motor circuit, heat from the burner may be used in such amount as may be required. When the lever is released, the spring operated plunger rises to open the burner circuit.

With the compression relieved a relatively 20 small starting motor will spin the engine at a high velocity, high enough to continue by momentum for a number of revolutions after compression has been restored, and a few moments only of such spinning and coincident heating suffices to start the engine on its normal cycle-produced by allowing the 25 plunger 38 to return to its half-way or full-up position. The auxiliary heat supplied by the burner suffices to produce, artificially, 30 the same, or an equivalent, temperature that is normally produced by the compression and sufficient to produce prompt ignition when starting from cold. The engine will pick up instantly. If desired to hasten the 35 starting, and in abnormal condition, the engine may be primed, for which purpose the branch 23 of the air intake passage is provided with an entrance 40 for liquid fuel, supplied to it from a connection 41 with the 40 fuel receptacle 42 of the burner. Admission of liquid fuel to this branch gives a hot mixture of air and fuel in the air heater 23 which is carried through the intake 22 to the engine where it is ignited by the 45 compression heat giving a series of impulses to the engine, further warming it, and thereby assuring prompt ignition of the injected fuel.

It will be understood that the engine is 50 provided with the usual or suitable means for fuel control adapted to regulate the amount delivered to the fuel injectors and that various other additions to, subtractions from and modifications of the structure hereinabove disclosed may be resorted to without departing from the invention.

Claims:

1. The combination in an internal combustion engine having means for altering 55 its valve action for temporarily converting it into a pump, an electric battery, an engine starting motor operated thereby, burner means for heating the engine inflow during the starting of the engine, and means for 60 restoring the normal engine valve action

while the engine is spinning under the motor-imparted energy.

2. The combination of an internal combustion engine, a battery-operated starting motor adapted to rotate the same to cause 70 influx of air thereto, a fuel supplying means, an enclosed liquid fuel burner operating independently of the said means adapted for coincidently heating said inflowing air and a single control member for jointly operating 75 said motor and liquid fuel burner.

3. The combination with an internal combustion engine, of a battery-operated starting motor adapted to rotate the same, means for supplying air to the engine when the latter is rotated by said motor, said air being unmixed with fuel, and an enclosed liquid fuel burner adapted for coincidently heating said inflowing air.

4. The combination in an internal combustion engine of means for altering its valve action for temporarily converting it into an air pump, a liquid fuel burner for heating the air flowing in through the intake and means for coincidently operating 90 said burner and rotating the engine.

5. The combination in an internal combustion engine of a starting motor adapted to rotate the same to cause influx of air thereto, independent means for supplying fuel and air to the engine, an enclosed liquid fuel burner for heating the inflowing air unmixed with fuel, and an electric battery connected to said motor and burner and adapted for operating both of them.

6. The combination in an internal combustion engine, of a starting motor therefor, means for delivering fuel liquid to the engine and an independent liquid fuel burner arranged to impart heat to the engine, and an electric battery connected for coincidentally starting the rotation of the engine and operating said burner.

7. The combination in an internal combustion engine, of an injection fuel valve to supply the fuel for the normal working operation, a separate passage for supplying air to the engine, a starting motor for the engine adapted to rotate the latter to cause influx of air thereto through said separate passage, means for heating the said inflowing air and independent means for admitting liquid fuel to said inflowing air.

8. In combination, an engine provided with a valve for injecting fuel into its combustion space or spaces for its normal working operation, a separate air intake passage, the engine being adapted to have its compression relieved, a starting motor arranged to spin the engine with its compression relieved, means for imparting heat to said separate air intake passage while the engine is spinning to heat the engine to facilitate starting, a source of energy for operating 120 said motor and heating means and means

for restoring the engine compression while the heated engine is spinning.

9. In combination, an engine having an air intake and means for injecting fuel into its compression space and adapted to have the compression relieved for starting, a starting motor for spinning the engine when its compression is relieved, means for heating the engine intake during the spinning to heat the air therein and by means of the heated air to heat the engine, and independent means for admitting liquid fuel to said intake.

10. In combination, an engine normally working by the injection of liquid fuel into an air charge in its combustion space, means for temporarily suspending said injection and compression, a starting motor for spinning the engine during such suspension and means for admitting a hot mixture of air and liquid fuel to the engine while it is spinning under the motor-imparted energy.

11. In combination, an engine normally working by the injection of liquid fuel into an air charge with ignition of said charge by the heat of compression, means for temporarily suspending the compression and fuel injection, a battery-driven starting motor adapted to spin the engine during such suspension, a battery-operated liquid fuel burner adapted to impart heat to the engine and means for restoring the compression and fuel injection while the engine is spinning.

12. In combination, an engine normally working by the injection of liquid fuel into an air charge ignited by the heat of compression, and having means whereby the exhaust gas may heat the inflowing air charge, a starting motor for rotating the engine to cause influx of air thereto, an enclosed liquid fuel burner for heating said inflowing air and a common source of energy connected to operate said motor and heater.

13. In an internal combustion engine, a branched intake passage having one branch

adapted to conduct an unheated gaseous medium to the engine, and an exhaust passage and a liquid fuel burner both in heat transmitting relation to the other branch.

14. In an internal combustion engine, means for converting the same into a pump, burner means for heating the gaseous medium flowing to the engine while the latter is acting as a pump, a starting motor for rotating the engine when converted and a single control member for said means and motor.

15. In an internal combustion engine, a liquid fuel burner, an engine turning motor, and a control member adapted by its initial movement to cause operation of said burner and by a further movement to cause operation of said motor.

16. The combination of an internal combustion engine, a fuel supplying means therefor, a battery-operated starting motor adapted to rotate the engine at starting and cause an influx of air to the engine, the said fuel supplying means being so arranged that no fuel is supplied to the engine thereby at a time when the starting motor is rotating the engine, and an enclosed liquid burner adapted to heat the said air influx while the motor is rotating the engine.

17. The combination of an internal combustion engine, means for injecting fuel into the engine cylinders, a passage for leading air into the engine cylinders, means for rotating the engine preliminary to starting, air being supplied to the engine through said passage during such preliminary rotation and the said fuel injecting means being arranged so that no fuel is supplied to the engine thereby during such preliminary rotation, and an enclosed liquid burner adapted to heat the air supplied to the engine through said passage during the preliminary rotation.

In testimony whereof, I have signed this specification.

JOHN GOOD
